UNITED STATES PATENT OFFICE.

ISAAC H. LEVIN, OF NEWARK, NEW JERSEY.

ELECTROLYTIC APPARATUS.

1,199,472.

Specification of Letters Patent. Patented Sept. 26, 1916.

Application filed June 3, 1916. Serial No. 101,468.

To all whom it may concern:

Be it known that I, ISAAC H. LEVIN, a citizen of the United States, residing at Newark, in the county of Essex and State 5 of New Jersey, have invented certain new and useful Improvements in Electrolytic Apparatus, of which the following is a specification, reference being had therein to the accompanying drawings, which form a 10 part thereof.

My invention relates to electrolytic apparatus and more particularly to such apparatus of the bi-polar electrode type.

Heretofore, in this art, it has been the accepted theory that in all electrolytic apparatus used in the production of oxygen and hydrogen, the current yield or capacity efficiency of the apparatus, or gases, produced with a given current, will be in direct 15 ratio to the purity of the gases produced. In apparatus using uni-polar electrodes, the correctness of this theory has been demonstrated; and heretofore it has been universally accepted as being also applicable to 20 apparatus using bi-polar electrodes. With apparatus of the last named type, however, the current yield or the quantity of gases produced with a given current, has always been far below the theoretical capacity efficiency of the apparatus according to the accepted law above referred to. This discrepancy in the yield, has been generally attributed by workers in the art, to wastage 25 through leakage of gases from the apparatus by reason of imperfect packing between the different electrodes entering into the apparatus.

I have heretofore made and used electrolytic apparatus of the bi-polar type wherein 30 sufficiently tight joints between adjacent electrodes have reduced the waste through leakage to a point of substantial elimination and have also built such apparatus wherein the percentage of impurities in the gases 35 is so small as to be negligible; but have found that with such apparatus, the current yield is materially below the theoretical capacity of the apparatus when measured by the law above referred to. The loss in 40 the yield is of a volume so great that a leak of the volume of gases thus unaccounted for would make the apparatus substantially inoperative. By experiment, I have determined that this loss of capacity efficiency 45 instead of occurring as a result of a leakage of gases from the apparatus, is the result of

leakage of a portion of the current delivered to the apparatus about the electrode in a manner to permit the flow of this current without its doing useful work in decomposing the electrolyte. In other words, loss in the capacity efficiency of the apparatus is the direct result of seepage of the electric current through the electrolyte feed duct or the communicating passages between adjacent cells and in some cases through the gas offtake ducts as well.

The capacity efficiency of an apparatus using a bi-polar electrode as compared with the law as above stated, even when a substantial wastage of gas through leakage is prevented by a perfect packing of the electrodes shows a loss of approximately 10%.

By means of my invention, I am enabled to produce an electrolytic apparatus using bi-polar electrodes wherein the current yield, or capacity efficiency of the apparatus, will substantially equal that of a uni-polar apparatus and will conform to the recognized and accepted law governing the operation of uni-polar apparatus. With an apparatus made in accordance with my invention, the capacity efficiency will be 100%, if absolutely pure gases are produced or a fraction under 100% where there are traces 50 of impurities in the gases. I secure this result by so constructing the electrodes that the flow of the current from adjacent one electrode to adjacent the other electrode is substantially prevented, thus causing all of 55 the current delivered to the apparatus to do work in decomposing the electrolyte by providing the communicating passages leading from one cell to another through which electrolyte or electrolyte and gas flows with 60 a device which will develop sufficient resistance to the flow of the current to insure the path of the current being substantially limited to the plates of the various electrodes, with that resultant increase in the capacity 65 efficiency of the apparatus above referred to.

The invention consists primarily in electrolytic apparatus of the bi-polar type embodying therein a plurality of bi-polar electrodes having communicating passages 70 through which electrolyte or electrolyte and gas flows from one cell to another, and means whereby the flow of electric current through said communicating passage from cell to cell is substantially prevented; and 75 in such other novel features of construction and combination of parts as are hereinafter 80

set forth and described and more particularly pointed out in the claims hereto appended.

Referring to the drawings:—Figure 1 is a vertical longitudinal section through the lower part of a group of bi-polar electrodes, different portions being on parallel planes to show the ducts on both sides of the diaphragm; Fig. 2 is a similar view of the upper part of the electrode; Fig. 3 is a section of a modified construction; and Fig. 4 is a section of a still further modified construction.

Like letters refer to like parts throughout the several views.

In apparatus of the character to which my invention relates a plurality of similar bi-polar electrodes are used, each of said electrodes comprising a continuous frame *a* 20 inclosing a plate *b* arranged substantially centrally of the width of said frame. Each electrode is separated from the adjoining electrode by means of a gas impervious diaphragm *c* the edge of which is clamped between the frames *a* of adjoining electrodes in a manner to form a liquid proof joint about the plate *b*.

The frame *a* of each electrode is provided at the bottom thereof with two lugs 30 *d*—*e* communicating respectively through the passage *d*'—*e*' with the interior of said frame adjacent opposite sides of the plate *b* and between said plate and a diaphragm *c*. When a plurality of electrodes are assembled in the apparatus, the openings of similar lugs *d*—*e* upon adjoining electrodes form a continuous duct through which electrolyte is delivered to the interior of the cell formed by adjoining electrodes, but upon 40 opposite sides of the diaphragm separating said electrodes.

At the top of each electrode, I provide similar lugs *f*—*g* communicating with the interior of the frame *a* upon opposite sides 45 of the plate *b* through passages *f*'—*g*'. The lugs *f*—*g* have openings extending therethrough which, when a number of electrodes are assembled in the apparatus, form continuous ducts communicating with each cell 50 on opposite sides of the diaphragm separating the adjoining frames forming that cell, through which ducts the gases generated in the apparatus pass from the cell. Ordinarily the lugs *d*—*e*—*f*—*g* upon adjoining electrodes are provided with insulating gaskets *h* forming a liquid and gas 55 proof joint between the lugs and about the openings therein.

The construction heretofore described is 60 that commonly used in electrolytic apparatus of the bi-polar type, my invention relating more particularly to that modification of the electrolyte feed or of the gas intake ducts, or of both, or of the passages leading 65 from said ducts to the several cells by reason

of which conduction of the current through these ducts is prevented or diminished to a point where any loss of current through this source is not appreciable. By insulating the ducts through the lugs *d*—*e*—*f*—*g*, the decomposition of electrolyte in any of said ducts with a resultant presence of impurities in the gases generated, may be prevented but my present invention is not designed to affect the purity of the products of the apparatus, but to avoid that loss of the electric current resulting in the reduction in the capacity efficiency of the apparatus in its entirety.

To secure the desired result various different arrangements of communicating passages through which the electrolyte or electrolyte and gas may flow from one cell to another may be used, some of which I have illustrated in the accompanying drawings.

In that type of apparatus in which the gas and hydrostatic pressures are so controlled as to keep the gas offtake ducts substantially free of electrolyte, it is merely necessary to apply my invention to the electrolyte feed duct; but where the electrolyte circulates through the gas offtake ducts as well, the construction of these ducts should also be modified in accordance with my invention. In fact to prevent the electrolyte in the ducts 95 and the passages extending from said ducts to the cell, acting as a conductor for the current, I provide conduits so constructed that the electrolyte therein will constitute a resistance to the flow of the current therethrough greater than the resistance of the cell proper but without materially interfering with the passage of the electrolyte or of the gases through said ducts. The electrolyte in the cell offers considerable resistance to the current, and by confining at least a part of the electrolyte in the several ducts alone or ducts and passages within sufficiently restricted area, the resistance encountered by the current may be raised in these ducts, or ducts and passages to a point which is higher than that encountered in the cell itself, thus limiting the path of the current to the plates *b*, the electrolyte contained in the cells and the diaphragms.

The portion of the conduit or passages relied upon to develop the resistance above referred to, to secure the highest efficiency, is preferably made of insulating material so as to limit the path of the electric current to the electrolyte.

In the form of the invention shown in Fig. 1, I provide the insulating gaskets *h* for the openings in the lugs *d*—*e*, with a passage of lesser diameter than the openings in said lugs, and provide the opposite sides of the gasket proper, with reduced rigid tubular extensions *h*'—*h*² projecting into the openings in said lug. By means of these extensions, I elongate the passage ex- 130

tending through the gasket from adjacent one electrode to adjacent another electrode and thus increase the resistance as compared with a passage of shorter length. In 6 this form of the invention, I also provide the passages $d'-e'$ with a lining of insulating material, said material projecting above the bottom of the opening in said lug and terminating adjacent the mouth of the 10 opening in the extension h' .

In Fig. 2 I have shown an adaptation of the structure above referred to to the top lugs of the apparatus.

In the form of the invention shown in 15 Fig. 3, I provide the opening in each of the lugs $d-e$ with a lining i of insulating material making this material entirely independent of the gasket h and of a thickness to materially reduce the dimensions of 20 the opening through said lug. In this form of the invention, the passages $d'-e'$ are each provided with an insulated lining, which project into the opening as shown. This construction may be duplicated with 25 the lugs $f-g$.

In the form of the invention shown in Fig. 4, I provide a gasket h having a simultaneous passage j therethrough to secure the desired additional length thereof, said passage being reinforced by a substantially rigid lining in a manner to prevent the collapse of the passage when pressure is applied to the gasket in assembling the apparatus.

35 Various other constructions may be adopted to secure the desired results, the showing in the accompanying drawings being merely an illustration of some of the different methods which may be used.

40 By providing a constricted passage extending between the openings in succeeding sections of the ducts, which sections are respectively in communication with the interior of the several electrodes, and so forming 45 said passage that the walls thereof will not themselves form a conductor for the current, I am enabled to prevent the flow of the electric current through said ducts to an extent to cause any substantial 50 diminution in the current yield, or capacity efficiency, of the apparatus.

So far as I have been able to determine, the constriction of this passage has the effect of an electrical resistance and in the 55 production of electrodes, it is necessary to proportion the length and cross section of this passage so as to develop the desired resistance to the current.

It is apparent that, if the flow of the current through the electrolyte feed ducts, or the gas intake ducts or both, is prevented, the current can flow only through the several cells where it will do useful work in decomposing the electrolyte.

65 In apparatus wherein the electrolyte cir-

culates in both the electrolyte feed ducts and the gas offtake ducts, it is necessary to equip all of the ducts with my invention to insure the highest efficiency; while if the electrolyte does not flow through the gas 70 offtake ducts, the wastage through these ducts may not be sufficiently great to necessitate the application of my invention thereto. To insure reliability in the operation of an apparatus made in accordance 75 with my invention, it is desirable to insulate and elongate the passages leading from the several ducts to the various cells, although by elongating the constricted passage connecting the duct sections themselves, this insulating lining for the passages may be dispensed with.

It is not my intention to limit the invention to the precise details of construction shown in the accompanying drawings, it being apparent that such may be varied to adapt the invention to different designs of electrodes or for other reasons, without departing from the spirit and scope of the 80 invention.

Having described the invention what I 85 claim as new and desire to have protected by Letters Patent is:—

1. An electrolytic apparatus embodying 90 therein a plurality of bi-polar electrodes forming a series of cells, an electrolyte feed duct common to all of said cells and means whereby the flow of the electric current from one electrode to another through said duct is substantially prevented.

2. An electrolytic apparatus embodying 95 therein a plurality of bi-polar electrodes forming a series of cells, a gas offtake duct common to all of said cells and means whereby the flow of the electric current from one electrode to another through said duct is substantially prevented.

3. An electrolytic apparatus embodying 100 therein a plurality of bi-polar electrodes forming a series of cells, electrolyte feed and gas offtake ducts common to all of said cells and means whereby the flow of the electric current from one electrode to another through said ducts is substantially prevented.

4. An electrolytic apparatus embodying 110 therein a plurality of bi-polar electrodes forming a series of cells, an electrolyte feed duct common to all of said cells, and an insulating medium forming a constriction in the path of the electrolyte between adjoining electrodes whereby a resistance is created sufficient to substantially prevent the flow of the current from one electrode to another through said duct.

5. An electrolytic apparatus embodying 120 therein a plurality of bi-polar electrodes forming a series of cells, a gas offtake duct common to all of said cells and an insulating medium forming a constriction in the path 125 of the electrolyte between adjoining electrodes whereby a resistance is created sufficient to substantially prevent the flow of the current from one electrode to another through said duct.

6. An electrolytic apparatus embodying 130 therein a plurality of bi-polar electrodes forming a series of cells, a gas offtake duct common to all of said cells and an insulating medium forming a constriction in the path of the electrolyte between adjoining electrodes whereby a resistance is created sufficient to substantially prevent the flow of the current from one electrode to another through said duct.

- of the electrolyte between adjoining electrodes whereby a resistance is created sufficient to substantially prevent the flow of the current from one electrode to another through said duct.
6. An electrolytic apparatus embodying therein a plurality of bi-polar electrodes forming a series of cells, electrolyte feed and gas offtake ducts common to all of said cells and an insulating medium forming constrictions in the paths of the electrolyte between adjoining electrodes whereby a resistance is created sufficient to substantially prevent the flow of the current from one electrode to another through said ducts.
7. An electrolytic apparatus embodying therein a plurality of bi-polar electrodes forming a series of cells, said electrodes respectively being provided with a lug having an opening therethrough, the openings in the lugs of respective electrodes forming a continuous electrolyte feed duct, passages extending from said duct and communicating with each of said cells, and a gasket of insulating material forming a packing about the openings in said lugs, said gaskets having reduced tubular extensions of insulating material whereby a portion of said duct between adjoining electrodes is constricted to form an electrical resistance sufficient to substantially prevent the flow of the current from one electrode to another through said duct.
8. An electrolytic apparatus embodying therein a plurality of bi-polar electrodes forming a series of cells, said electrodes respectively being provided with a lug having an opening therethrough, the openings in the lugs of respective electrodes forming a continuous gas offtake duct, passages extending from said duct and communicating with each of said cells, and a gasket of insulating material forming a packing about the openings in said lugs, said gaskets having reduced tubular extensions of insulating material whereby a portion of said duct between adjoining electrodes is constricted to form an electrical resistance sufficient to substantially prevent the flow of the current from one electrode to another through said duct.
9. An electrolytic apparatus embodying therein a plurality of bi-polar electrodes forming a series of cells, said electrodes respectively being provided with a lug at the top thereof, and a lug at the bottom thereof, each of said lugs having an opening therethrough, the openings in the several lugs of the respective electrodes forming continuous electrolyte feed and gas offtake ducts, passages extending from said ducts respectively and communicating with each of said cells, and a gasket of insulating material forming a packing about the openings through said lugs respectively, said gaskets respectively having reduced tubular extensions of insulating material whereby the passage from one cell to another is so constructed as to form an electrical resistance sufficient to substantially prevent the flow of the current from one electrode to another through said duct.
10. An electrolytic apparatus embodying therein a plurality of bi-polar electrodes forming a series of cells, said electrodes respectively being provided with a lug having an opening therethrough, the openings in the lugs of respective electrodes forming a continuous electrolyte feed duct, passages extending from said duct and communicating with each of said cells, a gasket of insulating material forming a packing about the openings in said lugs, said gaskets having reduced tubular extensions of insulating material, a lining of insulating material for said passages respectively whereby the passage from one cell to another is so constricted as to form an electrical resistance sufficient to substantially prevent the flow of the current from one electrode to another through said ducts and said duct.
11. An electrolytic apparatus embodying therein a plurality of bi-polar electrodes forming a series of cells, said electrodes respectively being provided with a lug having an opening therethrough, the openings in the lugs of respective electrodes forming a continuous gas offtake duct, passages extending from said duct and communicating with each of said cells, a gasket of insulating material forming a packing about the openings in said lugs, said gaskets having reduced tubular extensions of insulating material, a lining of insulating material for said passages respectively whereby the passage from one cell to another is so constricted as to form an electrical resistance sufficient to substantially prevent the flow of the current from one electrode to another through said ducts and said duct.
12. An electrolytic apparatus embodying therein a plurality of bi-polar electrodes forming a series of cells, said electrodes respectively being provided with a lug at the top thereof, and a lug at the bottom thereof, each of said lugs having an opening therethrough, the opening in the several lugs of respective electrodes forming continuous electrolyte feed, and gas offtake, ducts, passages extending from said ducts respectively and communicating with each of said cells, a gasket of insulating material forming a packing about the openings through said lugs respectively, said gaskets respectively having reduced tubular extensions of insulating material, and a lining of insulating material for said passages respectively whereby the passage from one cell to another is so constructed as to form an electrical resistance sufficient to substantially prevent the flow of the current from one electrode to another through said ducts and said duct.

trical resistance sufficient to substantially prevent the flow of the current from one electrode to another through said passages and said ducts.

13. An electrolytic apparatus embodying therein a plurality of bi-polar electrodes forming a series of cells, said electrodes having therethrough communicating passages through which electrolyte or electrolyte and gas may flow from one cell to another and means arranged in said passages

respectively whereby the flow of the electric current from one electrode to another through said passages is substantially prevented.

15

In witness whereof I hereunto affix my signature in the presence of two subscribing witnesses this 2nd day of June 1916.
